Assignees of S. H. SAILOR Design for Seven-plate Stand

DESIGNS
Stoves and Furnaces.
Cooking Stoves and Ranges.

Extended August 29, 1881. Reg. 6 744

DES 592

Dec. 591

Samuel H. Sailor of Philadelphia, Pa.

Assignor to

J. G. Abbott & Archilus Lawrence of same place.
Letters Patent No. 592 — Dated Aug. 23rd 1853.

The schedule referred to in these Letters Patent and making part of the same.

To all whom it may concern:

Be it known, that I, Samuel H. Sailor, of the City and County of Philadelphia, and State of Pennsylvania, have invented or produced a new and original Design in Stoves, called the
"Seven Plate Stove,"

and I do hereby declare that the following is a full, clear, and exact description of the same; reference being had to the annexed drawings forming a part of this specification, in which

Figure 1 is a side elevation of the stove.

Figure 2 is a plan of the same.

Figure 3 is a rear elevation; and

Figure 4, a front elevation.

In the several figures, but one half of symmetrical ornaments are given. — Similar letters indicate the same part.

The ornamented portions of this stove consist of the top plate A, base plate B, two side plates C, back plate D, front plate E, and door F. The vertical corners of the stove are embellished with the reeds a, and each side plate C is adorned with the scrolls b, bearing the foliage c, and sweeps d, the whole being arranged in the various details, substantially as shown in figure 1.

The back plate D and door F bear ornaments H and I, the former similar to the ornaments on the side plates, but having the configuration & arrangement set forth in figure 3, the latter composed of foliage, sweeps & scrolls, in low relief, arranged as delineated in figure 4. Upon the front plate E

is the inscription "Abbott & Lawrence" in raised capitals.

The top plate A overhangs the side, front, and back plates, and terminates in the wavy edge f, the overhanging portions being ornamented by sweeps e, and curves i, arranged and having the configuration shown in the drawings.

The base plate B bears in front the scrolls m and n, bead p, and sweeps q, which with the curved surface r terminated in bead t, form the rim of the hearth: the curved surface r bears the spiral ornament s. Upon the hearth is the inscription "Patented, Philadelphia, 1853", in raised capitals and numerals. The ornaments on the base plate have the configuration and arrangement set forth and shown in figures 1, 2 and 4.

What I claim as my production, and desire to secure by Letters Patent, is

The configuration and arrangement of the ornaments in bas-relief, and mouldings on the plates, A, B, C, D, & E, and door F, as set forth in this specification and annexed drawings, forming a new and ornamental design for a stove called the "seven plate stove".

In testimony whereof, I have hereunto signed my name before two subscribing witnesses.

Witnesses,

Charles Webb. }
